UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A MATCH-BOX.

SPECIFICATION forming part of Design No. 21,768, dated August 9, 1892.

Application filed May 27, 1892. Serial No. 434,676. Term of patent 3½ years.

To all whom it may concern:

Be it known that I, CHARLES OSBORNE, of New York, county and State of New York, have invented and produced a new and original Design for Match-Boxes or Similar Articles, of which the following is a specification.

In the accompanying drawings, Figure 1 is a front view of a match-box, showing my design. Fig. 2 is a transverse section thereof.

10 The leading feature of my design consists of an ornamentation in relief, having its base or starting-point at or near one of the corners of the box.

15 Referring by letter to the drawings, A designates a box having its general contour in waved lines, although said contour may be in straight lines without departing from the spirit of my design. From one corner of the box or from a point adjacent thereto an ornamental scroll extends in relief, and consists,

essentially, of downward and inward extending leaf-like forms a , the leaf-like scrolls a' near the center of the box, and the scroll a^2 , extending from a branched scroll a^3 . Within the ornamentation just described are flower-like figures $b b'$, corrugated circumferentially. The cover A' of the box has a flower-like figure c and a scroll c' extending therefrom.

Having described my invention, what I claim is—

20 The design for a match-box, substantially as herein shown and described.

In testimony whereof I have signed my name to this specification in the presence of two subscribing witnesses.

CHARLES OSBORNE.
